US00D610381S

(12) **United States Design Patent**
Stifal

(10) **Patent No.:** **US D610,381 S**
(45) **Date of Patent:** **** Feb. 23, 2010**

(54) **COVER**

(75) Inventor: **Matthew William Stifal**, Portage, IN (US)

(73) Assignee: **Peerless Industries, Inc.**, Melrose Park, IL (US)

(**) Term: **14 Years**

(21) Appl. No.: **29/344,808**

(22) Filed: **Oct. 5, 2009**

(51) LOC (9) Cl. **06-06**

(52) U.S. Cl. **D6/513**

(58) **Field of Classification Search** D6/553, D6/567, 555, 574, 474, 461, 468, 570, 569, D6/512, 513, 514; 108/40, 42, 35, 59, 91, 108/92, 96, 134, 115, 152; 211/87.01, 90.04, 211/90.02, 119.005, 126.5, 134, 40, 41.12, 211/42, 49.1, 50

(74) *Attorney, Agent, or Firm*—Foley & Lardner LLP

(57) **CLAIM**

I claim the ornamental design for a cover, as shown and described.

DESCRIPTION

FIG. 1 is a front perspective view of a cover showing my new design;

FIG. 2 is a rear perspective view thereof;

FIG. 3 is a front elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a rear elevational view thereof;

FIG. 9 is a front perspective view of another embodiment of a cover showing my new design;

FIG. 10 is a rear perspective view of the cover in FIG. 9;

FIG. 11 is a front elevational view of the cover in FIG. 9;

FIG. 12 is a top plan view of the cover in FIG. 9;

FIG. 13 is a bottom plan view of the cover in FIG. 9;

FIG. 14 is a right side elevational view of the cover in FIG. 9;

FIG. 15 is a left side elevational view of the cover in FIG. 9; and,

FIG. 16 is a rear elevational view of the cover in FIG. 9.

The broken lines shown are for illustrative purposes only and form no part of the claimed design.
